CLAIM

The ornamental design for a universal gas collector box for ignitor, as shown and described.

DESCRIPTION

FIG. 1 is a perspective view of a universal gas collector box for ignitor showing my new design;

FIG. 2 is a side elevational view thereof, the opposite side being a mirror image;

FIG. 3 is a front elevational view thereof;

FIG. 4 is a top plan view thereof;

FIG. 5 is a rear elevational view thereof; and,

FIG. 6 is a bottom plan view thereof.

The broken line showing of a portion of a barbecue grill burner in FIGS. 1 and 2 and a bolt in FIG. 2 is for illustrative purposes only and forms no part of the claimed design.
